CLAIM

The ornamental design for a clothing pocket for mobile device substantially as shown and described.

DESCRIPTION

FIG. 1 is a front view of clothing pocket for a mobile device shown in an environment of use;

FIG. 2 is another front view of the clothing pocket for a mobile device shown in an environment of use and containing a mobile device;

FIG. 3 is an enlarged perspective view of the clothing pocket for a mobile device of FIG. 2;

FIG. 4 is a top view thereof;

FIG. 5 is a right side view thereof;

FIG. 6 is a left side view thereof;

FIG. 7 is a front view thereof; and,

FIG. 8 is a bottom view thereof.

The broken lines illustrating the shirt represent environment of the claim that form no part of the claimed design. The broken lines illustrating the square boundary in FIGS. 3-8 represents boundaries of the enlarged view and form no part of the claimed design. The mobile device illustrated in FIGS. 2-8 represents environment and forms no part of the claimed design.

1 Claim, 7 Drawing Sheets
